United States Patent

Des. 238,303

Patented Dec. 30, 1975

238,303

PAIR OF SPECTACLES

Conrad Leblanc, Leominster, Mass., assignor to Foster Grant Co., Inc., Leominster, Mass.

Filed Feb. 22, 1974, Ser. No. 445,043

Term of patent 14 years

Int. Cl. D16—06

U.S. Cl. D57—1 F

FIG. 1

FIG. 2

FIG. 3

FIG. 4

FIG. 5

FIG. 6

FIG. 1 is a perspective view of a pair of spectacles showing my new design.

FIG. 2 is a front elevational view thereof showing the spectacle front pivoted to a generally horizontal position out of the line of sight of the user.

FIG. 3 is a rear elevational view thereof.

FIG. 4 is a front elevational view thereof.

FIG. 5 is a front elevational view of another embodiment of my new design.

FIG. 6 is a front elevational view of still another embodiment of my new design.

FIGS. 1, 2 and 3 of the drawing disclose the configuration of all embodiments of my new design except for the differences in front configuration of the embodiments disclosed in FIGS. 5 and 6.

The side not shown has substantially the same appearance as the side shown.

I claim:

The ornamental design for a pair of spectacles, substantially as shown and described.
